UNITED STATES PATENT OFFICE

WILLIAM G. WAGENHALS, OF DETROIT, MICHIGAN

HUMIDIFIER

Application filed April 28, 1930. Serial No. 447,950.

The present invention pertains to a novel air humidifier or moistener of a type particularly adapted for preserving cigars, cigarettes or other tobacco products in their original moist condition and for preventing the same from becoming dry while placed in display cases or cabinets.

The primary object of the present invention is to devise an air humidifier of a compact portable nature facilitating its insertion in display cases or cabinets of the type used for displaying cigars, cigarettes and other tobacco products. The present humidifier is provided with a water receptacle in which is received portions of capillary plates, the upper portions of the plates being subjected to a flow of air created by an electric fan mounted upon the receptacle supporting base, this arrangement facilitating more efficient moistening of the air than is possible by conventional humidifiers due to the fact that it assists the evaporation or dissipation of the water from said capillary plates.

Another object of the present invention is to devise an air humidifier which, although particularly adapted for use in preserving tobacco products, is also capable of efficient service as a domestic humidifier for moistening the atmosphere within a dwelling or public building.

With the above and other ends in view the invention consists in the matters hereinafter set forth and more particularly pointed out in the appended claims, reference being had to the accompanying drawings, in which

Figure 1 is a perspective view of the present humidifier, and

Fig. 2 is a top plan view.

Like characters of reference are employed throughout to designate the corresponding parts.

The numeral 1 indicates an elongated base upon which is mounted the vertically extending cut-away side walls 2 and end walls 3, formed in the nature of corner brackets. A receptacle 4, preferably formed of glass in order to be of a transparent nature is supported upon the base 1 by the walls 2 and 3, the receptacle being provided to contain a supply of water and the walls being cut away

to permit the container to be readily seen in order that the water therein may be maintained at a suitable level.

In construction, as may be clearly understood with reference to Fig. 1, each wall 2 is formed of a sheet of metal with a portion 3 being bent at right angles thereto, both the portions 2 and 3 being provided with an in-turned flange 5 facilitating the attachment to the base 1.

A cover plate 6 is provided for the receptacle 4 and is preferably formed from sheet metal having downturned flanges 7 and 8 which embrace the sides of the receptacle in a manner preventing the accidental displacement of the cover. The cover is provided with a plurality of elongated slots 9 in which are inserted metal frames 10 which contain a capillary material which facilitates the ascent of water from the level in the container to the top of the cover plate 6.

The particular arrangement of the slots 9 contribute to the efficiency of the present device, it being observed in reference to Fig. 2, that the central slot is formed parallel to the longitudinal axis of the base 1 while the other two slots are formed at an acute angle relative thereto, the ends of the slots which are nearest to the front of the receptacle being the two ends which are closest together. It therefore becomes apparent that a current of air passing along the longitudinal axis of the base would necessarily be converged and the flow retarded as it contacts with the members 10, the latter acting as baffles.

Mounted upon the rear portion of the base 1 is an electric fan 11 adapted to create a flow of air along the line of the longitudinal axis of the base which strikes against the capillary material supported in the frames 10 in a manner whereby the water is rapidly evaporated or dissipated and carried away by the air, thereby providing moisture laden air.

Although a specific embodiment of the present invention has been illustrated and described it is to be understood that various changes may be made in the details of construction without departing from the spirit of the invention, and such changes are contemplated.

What I claim is:

1. A humidifier comprising a base having a fan mounted thereon, vertical walls mounted upon said base, a water containing receptacle supported upon said base by said vertical walls, a plurality of capillary plates inserted in said receptacle to project upwardly therefrom, and a cover plate for said receptacle having slots arranged to support said capillary plates whereby the latter obstruct the flow of air created by said fan.
2. The combination with a base having vertically extending walls mounted thereon, of a water containing receptacle retained upon said base by said walls, capillary plates supported in said receptacle to project upwardly therefrom, and an electric fan mounted upon said base to create an air current which contacts with the projecting portions of said capillary plates.

In testimony whereof I affix my signature.

WILLIAM G. WAGENHALS.
